[57] CLAIM

The ornamental design for a folding tool box, as shown and described.

DESCRIPTION

FIG. 1 is a top, front and right side perspective view of a folding tool box showing my new design;

FIG. 2 is a top plan view thereof;

FIG. 3 is a right side elevational view thereof;

FIG. 4 is a front elevational view thereof;

FIG. 5 is a rear elevational view thereof;

FIG. 6 is a left side elevational view thereof;

FIG. 7 is a bottom plan view thereof; and

FIG. 8 is a rear elevational view thereof, showing the box in unfolded position.

FIG. 9 is a top plan view thereof with the box in its completely unfolded disposition.

FIG. 1.

Fig. 2.

Fig. 3.

Fig. 4.

FIG. 5.

FIG. 6.

FIG. 7.

Fig. 8.
